[57] CLAIM

The ornamental design for a face plate, as shown and described.

DESCRIPTION

FIG. 1 is a perspective view taken from the front and right side of a face plate showing my new design;

FIG. 2 is a front elevational view thereof;

FIG. 3 is a top plan view thereof;

FIG. 4 is a right side elevational view thereof, the left side being a mirror image of the right side shown;

FIG. 5 is a bottom plan view thereof;

FIG. 6 is a rear elevational view thereof;

FIG. 7 is an enlarged detail of a cross sectional view

taken on a segment of line 7—7; and,

FIG. 8 is a front elevational view of an alternative embodiment thereof, the embodiment being the same as the embodiment of FIGS. 1-7 except that FIG. 8 is the mirror image of FIG. 2.

The fragmentary broken line representation of mounting holes in FIGS. 1, 2, 5, 6 and 8 is for the purpose of illustration only and forms no part of the claim design.

FIG. 2

FIG. 3

FIG. 4

FIG. 7

FIG. 5

FIG. 6

FIG. 8
